CLAIM

The ornamental design for a patient circuit for gas delivery, as shown and described.

DESCRIPTION

FIG. 1 is an isometric view of a patient circuit for gas delivery showing our new design;

FIG. 2 is a front view of FIG. 1;

FIG. 3 is a back view of FIG. 1;

FIG. 4 is a right side view of FIG. 1;

FIG. 5 is a left side view of FIG. 1;

FIG. 6 is a top view of FIG. 1; and,

FIG. 7 is a bottom view of FIG. 1.

The portions of the patient circuit for gas delivery shown in broken lines that form no part of the claimed design.

1 Claim, 7 Drawing Sheets(56)
